Primary Examiner — Michael C Stout*Assistant Examiner* — Fitzgerald L Butac(74) *Attorney, Agent, or Firm* — Moritt Hock & Hamroff LLP; Bret P. Shapiro**CLAIM**

We claim the ornamental design of a sleeve-ball split bearing housing, as shown and described herein.

DESCRIPTION

FIG. 1 is a top rear perspective view of a sleeve-ball split bearing housing, according to the new design;

FIG. 2 is a bottom rear perspective view thereof;

FIG. 3 is a rear elevation view thereof;

FIG. 4 is a front elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines show portions of a sleeve-ball split bearing housing which form no part of the claimed design.
